ORNAMENTAL CLIP

William Huppert, New York, N. Y., assignor to
Delamere Company, Inc., a corporation of Del-
aware

Application June 25, 1937, Serial No. 150,282

1 Claim. (Cl. 24—248)

This invention relates to ornamental clips, and more particularly to clips of the kind commonly known as dress clips.

The principal object of the invention is to provide the clip with gripping means of such character that no fabric, however delicate, will be injured thereby.

According to my invention the gripping means consist of an arrangement of rubber or other resilient, soft, non-metallic teeth secured to the back plate or clamping member of the clip.

One feature of the invention is that the metal prongs or teeth heretofore used on clips of this type may, in various modifications of the invention, be conveniently employed as anchorages for the gripping means.

Other objects and features of the invention will appear more fully from the following description thereof, reference being had to the accompanying drawing, in which:

Fig. 1 is a view from the rear of one embodiment of the clip, the back plate and face plate being in fabric gripping relation to one another;

Fig. 2 is a view in side elevation of the structure shown in Figure 1;

Fig. 3 is a view in cross-section, taken on the line 3—3 of Figure 1, looking in the direction of the arrows;

Fig. 3a is a view in cross-section, taken on the line 3a—3a of Fig. 3, looking in the direction of the arrows;

Fig. 4 is a fragmentary rear view of the back plate of a clip having a cross-piece provided with a modified form of gripping means;

Fig. 5 is a view in cross-section, taken on the line 5—5 of Fig. 4, showing the gripping means in effective position with relation to the face plate;

Fig. 6 is a view similar to that of Fig. 5 illustrating another modification of the invention;

Fig. 7 is a fragmentary rear view of the back plate of a clip showing a further modification of the gripping means; and

Fig. 8 is a view in cross-section, taken on the line 8—8 of Fig. 7, showing the gripping means in effective position with respect to the face plate.

Referring now to the drawing, a preferred form of the invention is shown in Figs. 1, 2, 3 and 3a. In this form, the clip comprises a face plate 10, of any desired configuration, design or ornamentation, and a back plate 11 hinged to the face plate. The garment or fabric to which the clip is to be attached is gripped and held between these two elements. The hinge connection of the back plate 11 to the face plate 10 may be of any known form. In the form illustrated, the face plate has ears 12 provided with perforations to receive the pivot pins 13 of the back plate 11. A leaf spring 14 or other suitable means is provided

for urging the back plate 11 into its closed or gripping position.

The back plate 11 has two prongs 15 stamped toward the face plate 10 from the sheet material of which the back plate is made. Each of these prongs 15 serves as an anchorage for a tooth 16 of rubber or other resilient, or soft, non-metallic material. As indicated in Fig. 3a, the prongs 15 preferably have enlarged heads 17 which are snapped into recesses in the teeth 16 to hold 10 the latter securely in place.

The openings 18 shown in the face plate 10 of Fig. 1 are formed primarily for ornamentation. However, these openings may serve to provide a more or less positive interlockment of the fabric 15 with the face plate. On referring particularly to Figs. 3 and 3a, it will be seen that in the closed position of the back plate, the tips or upper ends of the rubber teeth 16 protrude slightly into the openings. Such positive interlockment of the 20 fabric with the face plate is, however, ordinarily unnecessary, as the resiliency of the teeth may be relied upon sufficiently to grip any ordinary fabric.

In Figs. 4 and 5 a modification of the invention is shown wherein the back plate 11 of the clip has a cross-piece 19 out of which are stamped a plurality of headed prongs 20 of the same style as those shown in Fig. 3a. In this form of clip, there are no openings in the face plate into which 30 the ends of the resilient teeth protrude.

Another modification is shown in Fig. 6 wherein the three resilient or rubber teeth 21 are molded or formed in one piece and are of a slightly different shape.

A further modification of the invention is illustrated in Figs. 7 and 8. In this instance, the prongs are eliminated and the cross-piece 22 of the back plate 11 has an opening into which fits a rubber or resilient pad 23 having a plurality 40 of teeth or serrations 24 formed thereon. The pad 23 has notches 25 in its sides for engagement of the edges of the opening in the cross-piece 22, the pad being sprung into place in the opening of the cross-piece.

Various modifications in the details of construction herein illustrated and described may be resorted to within the scope and spirit of the invention as defined in the claim.

What I claim is:—

A dress clip comprising a face plate and a back plate hinged together, a spring normally holding said plates in closed position, an opening in the back plate for the reception of a pad, a pad having resilient teeth projecting toward the front 55 plate for engagement therewith when the plates are closed, said pad having recesses in its sides for engagement in the edges of the opening in the back plate.

WILLIAM HUPPERT. 60
